US0D1017575S

(12) **United States Design Patent** (10) **Patent No.:** **US D1,017,575 S**
(45) **Date of Patent:** **** Mar. 12, 2024**

(54) **EARCUP FOR HEADPHONES**

(71) Applicant: **ODM GmbH**, Wattenheim (DE)

(72) Inventors: **Christopher Kühn**, Obrigheim (DE);
Torben Mang, Mannheim (DE); **David Pflüger**, Sembach (DE)

(73) Assignee: **ODM GMBH**, Wattenheim (DE)

(**) Term: **15 Years**

(21) Appl. No.: **35/514,525**

(22) Filed: **May 6, 2022**

(80) **Hague Agreement Data**

Int. Filing Date: **May 6, 2022**

Int. Reg. No.: **DM/221346**

Int. Reg. Date: **May 6, 2022**

Int. Reg. Pub. Date: **Jul. 1, 2022**

(30) **Foreign Application Priority Data**

Nov. 8, 2021 (DE) 40 2021 101 015.7

(51) **LOC (14) Cl.** **14-01**

(52) **U.S. Cl.**

USPC **D14/205**; D29/112
